(57) **CLAIM**

The ornamental design for an vertical microphone array, as shown and described.

DESCRIPTION

FIG. 1 is a perspective view of a vertical microphone array showing the rear and right side of our new design;

FIG. 2 is front elevation view of the vertical microphone array of FIG. 1;

FIG. 3 is a rear elevation view of the vertical microphone array of FIG. 1;

FIG. 4 is a right side elevation view of the vertical microphone array of FIG. 1;

FIG. 5 is a left side elevation view of the vertical microphone array of FIG. 1;

FIG. 6 is a top plan view of the vertical microphone array of FIG. 1; and,

FIG. 7 is a bottom plan view of the vertical microphone array of FIG. 1.

The broken lines in FIGS. 1 and 3 are for illustrative purposes only and forms no part of the claimed design.
